United States Patent Office.

JOHN H. BARNES, OF BROOKLYN, NEW YORK.

Letters Patent No. 60,668, dated January 1, 1867; antedated December 2, 1866.

IMPROVED GROOVED WHEELS OR PULLEYS.

The Schedule referred to in these Letters Patent and making part of the same.

TO ALL WHOM IT MAY CONCERN:

Be it known that I, JOHN H. BARNES, of Brooklyn, in the county of Kings, and State of New York, have invented a new and useful Improvement in Grooved Wheels, Rollers; or Pulleys; and I do hereby declare that the following is a full, clear, and exact description thereof, reference being had to the accompanying drawings, and to the letters of reference marked thereon, and making a part of this specification.

The character or nature of my invention consists in an improved construction of grooved wheel, roller, or pulley, which can be made or produced much cheaper than the ordinary grooved wheel, and in the use of which there is far less liability of the rope or cord being thrown off the wheel, and when off, it can be much more easily put on again.

Figure 1 represents a grooved roller, constructed according to my invention, and suitable to be applied to a window-shade.

Figure 2 represents a wheel or pulley constructed on the same plan.

Figures 3 and 4 are edge views of fig. 2, showing the cord passing over it in two positions.

Grooved wheels, pulleys, &c., as heretofore formed and constructed, have had in their periphery a continuous groove, for the reception of the rope or cord, or a groove, the sides or lips of which are continuous or unbroken entirely around the wheel or pulley. As a necessary consequence of such form of construction, whenever the rope or cord becomes by any means lifted or thrown up out of the groove, and upon or over the edge or top of the lip of the groove, the danger or liability of the cord being thrown entirely off the wheel is continually increased as the wheel revolves, as there is nothing in the form either of the wheel or of its groove to check the cord or rope, or hold it in the groove. The construction or casting of a wheel or pulley with a continuous groove is also difficult and expensive, for the reason that the pattern which has to be used in moulding cannot be made in one or a single piece, but is what is termed a divided pattern, that is, made in two or three separate pieces, and when the mould is prepared, one part of the pattern has first to be removed, and then the flask containing the mould has to be turned over or reversed, and the other part of the pattern removed. Much more time is thus consumed in moulding than would be required if the pattern was in a single piece, and could be "drawn" from the mould without the necessity of reversing or turning it. This consumption of time in moulding increases necessarily the cost of construction. My invention consists in giving to the wheel or pulley such a form of groove, that any tendency of the cord or rope to pass off from the wheel, even when it may get upon or over the top or edge of the groove, is counteracted and overcome, and such new form of groove also enables me to produce or manufacture the wheel or pulley much cheaper than heretofore, as it renders it possible to construct the pattern in a single piece, and such that it can be "drawn" from the mould, thus rendering unnecessary the turning of the mould, and saving the time heretofore thus consumed. Instead of having the groove in the periphery of the wheel continuous, or with uniform and complete sides or edges, as heretofore formed, the sides of the groove are cut away at regular intervals and to uniform extents, as represented in the drawings, thus forming a groove with regularly broken or intermitting sides. The opposite sides of the groove are also so cut away that the removed portions of one side of the groove are opposite the portions of the other side of the groove that are not cut away. In the drawings those portions of the opposite sides of the groove which are not cut away, or which project, are indicated by the figures 1, 2, 3, 4, 5, 6, 7, &c., and the corresponding portions which are removed are indicated by the letters *a*, *b*, *c*, *d*, *e*, *f*, *g*, &c. As before stated, those portions of the groove that are not removed are usually equal with each other, as are also those portions which are cut away; but such uniformity or regularity is not essential. The portions that are cut away from either side of the groove should, however, exceed somewhat in length the portions that remain, and that stand opposite the places where such parts have been cut away, so as to allow of the drawing of the sand in moulding. If these were all equal in extent, the pattern could not be drawn without injuring or destroying the mould. More than one-half of each side of the groove may be so cut away or removed, without affecting its action as such, thus making the wheel or pulley so much the lighter, and by so much also reducing the cost of material. When a cord or rope is passed over a wheel having such an intermitting groove, or a groove with broken sides, as is represented in fig. 3, it retains its proper position as well as when the wheel has a groove with continuous sides, the arrangement of the non-removed portions of the opposite sides making the groove equivalent to a continuous one. If, however, by any chance, the cord or rope

gets out of the groove, as shown in fig. 4, it will not be thrown entirely off the wheel, as it will be caught against or be stayed by the next projecting portion of the groove. The liability of the cord passing off the wheel is thus materially diminished, and the effect or tendency of such broken-sided groove is to keep the cord on the wheel. When the cord has been purposely or otherwise thrown off the wheel, such form or construction of groove also enables the wheel to be quicker and easier banded, as the cord or band will catch over or upon any projecting portion of the groove, and be at once carried upon the wheel by its revolution. Such form of groove also renders it possible, as before stated, to construct the pattern in a single piece, and such that it can be "drawn" from the mould, and does away with the necessity of a divided pattern, and the turning or reversing of the mould to remove it. It therefore effects a very great saving in the cost of constructing the wheel or pulley, by requiring ~~so~~ much less time in moulding, in addition to reducing the quantity of metal used in its manufacture. By these two items or particulars, the cost of construction will be reduced, it is believed, full twenty per cent. When a pattern is what is called a divided pattern, that is, of two or more parts, each part has to be numbered, and in moulding care has to be taken that the several parts of each pattern are brought and used together, and as each part is used, it has to be carefully brushed, so that no dirt or sand shall be left in it to mar the casting. These manipulations consume time and increase cost, all of which is avoided and saved in cases where the pattern can be made in a single piece, and can be drawn from the mould. The form of the groove hereinbefore described, that is, with broken or cut away sides, is also such as to allow the wheel or pulley to be "struck up" by suitable male and female dies, from sheet brass or other metal. The metal will first be cut out in suitable shape, and its periphery divided to the depth of the required sides of the groove, and the blank then subjected to proper dies, by the action of which the divided parts of the periphery will be carried to the opposite sides of the wheel alternately, and properly inclined and shaped, so as to form the sides of the groove.

What I claim as my invention, and desire to secure by Letters Patent, is—

A grooved wheel or pulley, having the opposite sides of the groove entirely cut away or removed, substantially as described, so as to permit the wheel or pulley to be cast or struck up, substantially as and for the purposes set forth.

JOHN H. BARNES.
